UNITED STATES PATENT OFFICE.

JOHN R. REYBURN, OF FAIRFIELD, CONNECTICUT, ASSIGNOR TO AMERICAN CHAIN COMPANY, INCORPORATED, OF BRIDGEPORT, CONNECTICUT, A CORPORATION OF NEW YORK.

COILED-WIRE SASH-CHAIN-ATTACHING DEVICE.

1,418,972.

Specification of Letters Patent. Patented June 6, 1922.

Application filed March 16, 1921. Serial No. 452,818.

To all whom it may concern:

Be it known that I, JOHN R. REYBURN, of Fairfield, Fairfield County, State of Connecticut, have made a new and useful Invention Relating to Coiled-Wire Sash-Chain-Attaching Devices, of which the following is a specification, taken in connection with the accompanying drawing, which forms a part of the same.

10 This invention relates especially to sash chain attaching devices formed of coiled wire and adapted to readily and efficiently secure sash chains to window sashes provided with the ordinary chain grooves and securing holes. This application is a continuation in part, that is, it contains subject-matter taken from my co-pending applications, 95,550, filed May 5, 1916, and 125,641 filed October 14, 1916.

20 In the accompanying drawings showing in a somewhat diagrammatic way illustrative embodiments of this invention,

Figure 1 is a perspective view showing one form of the attaching device.

25 Figure 2 is a side elevation of a sash to which this device has been secured.

Figure 3 is a similar view of another sash and device.

30 Figure 4 is a perspective view showing another form of attaching device secured to a sash chain and ready for insertion into the sash.

Figure 5 is a side elevation of the sash to which this device has been secured; and

35 Figure 6 is a perspective view of this form of device on a somewhat larger scale.

Figure 7 is a view in perspective of a modified form of the device.

40 The attaching device may be conveniently and effectively formed of coils of wire of galvanized iron or any other suitable material, the wire being of such size and stiffness as to have the desired strength and rigidity and also preferably being small enough so as to readily allow it to pass into the regular sized loops or eyes of the sash chain on which it is to be used. It is desirable to provide the attaching device with a radially projecting hanger loop having a

45 greater or less length and which may be conveniently formed on the device by sufficiently extending one of its securing members of suitable shape to cooperate with the securing hole of the sash and preferably

having the coiled form indicated so as to 55 provide an outwardly extending loop adapted to cooperate with the sash chain and maintain the desired connection therewith both before and after the attaching device is secured to the sash. It is desirable to 60 have this loop project sufficiently so that its inner portions form wedging aligning shoulders which are adapted to have wedging engagement with the sides of the usual securing hole in the sash and thus positively prevent 65 turning of the device after it has been forcibly inserted as well as preventing its accidental withdrawal from the hole. As indicated in Figures 1 to 3 this hanger loop 1 may in some cases have a very considerable 70 radial extension from the coils of the device and the sides 2 and 3 of this loop preferably tend to spring outward so as to wedge against the sides of the sash groove 15 adjacent the securing hole 10. For this purpose the sides of this loop may be curved outward so as to form the wedging aligning shoulders 6, 7 adjacent the securing members or coils of the device so that these shoulders tend to wedge themselves into the upper 75 corners 11 of the sash between the securing hole and groove. With this form of loop it is not necessary in all cases that the coils of the device should be of such diameter as to tightly engage the securing hole in the 80 sash, since as indicated in Figure 2 the coils 4, 8 may be considerably smaller in diameter than this securing hole which allows the attaching device to be effectively used in old sash or in sash in which the securing holes 85 are oversize in which case as illustrated the coils may fit loosely within the hole in which the device is securely retained in position by the action of its wedging aligning shoulders. If desired, one or both of the coils may in 90 some cases be formed with a retaining end, such as 9, which may extend downward into depending position so as to engage and be embedded in the lower side of the securing hole when the device is hammered or otherwise 95 forcibly inserted into the same.

100 It is of course more desirable, however, to have the coils of the device of substantially the same size as the securing hole so that, for example, the coils 4 and 8 fit more tightly 105 within the securing hole 10, as indicated in Figure 3, so that the retaining end coil 8 which is preferably of somewhat larger

diameter than the coil 4, fits tightly in the hole and positively retains the device in position in connection with the sash aside from the holding or locking engagement secured 5 through the action of the projecting retaining end 9 or the wedging aligning shoulders 6, 7. In this way the device which may in some cases have its attaching loop project radially to a less extent than indicated, may 10 be conveniently used with different sized sash or sash in which the securing holes and grooves are either oversized or enlarged by wear, and this is in many cases desirable especially in repair and renewal work, since 15 the attaching device automatically accommodates itself to these variations in the size and secures effective holding engagement with the sash regardless of such differences. To facilitate insertion of the device into the 20 eye or loop 13 of the sash chain 14 the device may be provided with one or more loosely coiled inserting ends, such as 5, this loop or coil being so loosely coiled upon itself that its end is laterally spaced away 25 from the adjacent turn or coil 4 of the device so that the chain loop may be conveniently run around the same and worked up into the hanger loop, about in the position indicated in Figures 2 and 3. The other coil 8 may, 30 if desired, be tightly coiled so that each coil or turn thereof is in substantial contact with the adjacent coils so that the accidental disengagement of the chain is thus prevented, especially when this tightly wound coil 8 is 35 on the outside as the device is inserted in the sash.

Another form of the coiled wire attaching device is shown in Figs. 4 to 6 in which the radially projecting hanger loop, such as 21, 40 may be conveniently formed by extending one of the coils of the device sufficiently to provide an outwardly extending loop adapted to cooperate with the sash chain and maintain the desired angular position of the device 45 in connection with the chain both before and after the attaching device is secured in the sash. It is desirable to have this loop project sufficiently so that its upper portions form wedging aligning shoulders 16 which 50 are adapted to have wedging engagement with the sides of the usual securing hole in the sash, and thus positively prevent turning of the device after it has been forcibly inserted. For this reason and to prevent axial 55 movement also some of the coils of the device are preferably made of such diameter as to tightly engage the securing hole in the sash either with or without relation to the wedging action of such a projecting loop or aligning member so as to more securely hold the 60 device in position. For this purpose some of the coils of the device such as the coiled retaining end 18 may if desired be staggered or formed of relatively large diameter so as 65 to resiliently and tightly engage the securing

hole when forced into the same, and if desired this retaining end 18 may be tightly coiled so that, for instance, the consecutive convolutions are normally in substantial contact with each other so that the tip 20, for 70 instance, which may extend downward into the depending position indicated is in substantially tight contact with the adjacent turn of this retaining end of the device. If desired also this tip 20 of the retaining end 75 may project outwardly radially somewhat beyond the adjacent coil so as to have additional securing action and embed or wedge itself into the side of the retaining hole when the device is inserted. To facilitate insertion 80 of the device into the eye or loop 13 of the sash chain 14 the device may be provided with a loosely coiled inserting end 19 which is also preferably though not necessarily of somewhat smaller diameter than 85 the retaining end of the device. In this way as indicated in the drawing the tip 17 of this loosely coiled inserting end is laterally spaced away from the adjacent coil of the device and may, if desired, have its upwardly extending end located adjacent the attaching loop 16.

In using this form of the device the tip 17 of the inserting end may be inserted into the eye 13 of the sash chain 14 and the device 90 turned to bring the hanger loop 21 into engagement with the chain end so that the device is substantially in the position shown in Fig. 4 is ready for insertion into the securing hole 10 of the sash. It is preferable to first 100 insert the hanger loop in the securing hole and then to force the coiled body of the attaching device into the hole as by hammering it in so that the aligning shoulders 16 are forced tightly home against the cooperating 105 parts of the sash and more or less wedge or embed themselves into the corners 11 formed at the upper part of this securing hole where it is intersected by the usual chain groove 15. Under these conditions the retaining end of 110 the device which is preferably of such diameter as to snugly engage the securing hole is simultaneously forced into tight engagement therewith, the radially projecting securing tip 20 of this retaining end also tending to embed itself slightly in the wood at the bottom of the securing hole, as shown in Fig. 5, so as to have a further retaining action and tend to minimize accidental displacement or working loose of the device 115 under service conditions. This forcible insertion or driving home of the device in the securing hole naturally tends to compress the loosely coiled inserting end which is preferably first inserted and these coils are 120 thus preferably forced together and tend to be held in closer engagement.

In Figure 7 I show a modified form of the device in which the projecting hanger loops are omitted. In this form some of the coils, 130

- for instance that indicated by 22, are preferably made of such diameter as to tightly engage the securing hole, and resistance to turning in the hole is created by the tip 20, 5 as in the other cases. The remaining coils are of progressively decreasing diameter to facilitate insertion in the hole and the device is secured to a chain by threading it through a link as shown.
- 10 This invention has been described in connection with a number of illustrative embodiments, forms, proportions, arrangements, materials and uses, to the details of which disclosure the invention is not of course to be limited, since what is claimed as 15 new and what is desired to be secured by Letters Patent is set forth in the appended claims.
1. The coiled wire attaching device for 20 sash chain having a tightly coiled retaining end coil and having a loosely coiled insert-
- ing end coil adapted to be readily inserted in the end of the sash chain, said coils being of such large diameter as to be retained in the securing hole of the sash and being connected by a hanger loop projecting radially from said coils a distance several times as great as the diameter of said coils. 25
2. The coiled wire attaching device for sash chain having a coiled retaining portion 30 to be retained in the securing hole of the sash and having a projecting securing tip to embed itself in the sash and a connected hanger loop having a wedging aligning shoulder adjacent said coiled portion and 35 projecting radially from said coiled portion a distance at least equal to the diameter thereof to enter the chain groove in the sash.

JOHN R. REYBURN.
